SHAMPOO SQUEEZE BOTTLE

Eino K. Marttinen, Westendin Puistotie 45, Helsinki
Westend, Finland

Filed Sept. 29, 1964, Ser. No. 81,909

Term of patent 14 years

(Cl. D58—6)

FIG. 1

FIG. 2

FIG. 1 is a front elevational view of a shampoo squeeze bottle, showing my new design;

FIG. 2 is a side elevational view thereof;

FIG. 3 is a plan view thereof; and

FIG. 4 is a bottom plan view thereof.

The rear of the shampoo squeeze bottle is the same in appearance as the front and the side not shown is the same in appearance as the side shown.

I claim:

The ornamental design for a shampoo squeeze bottle, as shown and described.
